to Tudor Metal Products Corporation, Brooklyn, N.Y.,
a corporation of New York

Filed Aug. 11, 1966, Ser. No. 3,429

Term of patent 14 years

(Cl. D34—5)

The figure is a perspective view of a bowling game target showing my new design. The opposite side of the target is substantially the same as that shown.

The dominant features of my design reside in the full line portions shown and is characterized by the U-shaped configuration of the support which is disposed to rest on one of the legs of the U, the other leg thereof being forwardly tapered, all as shown.

I claim:

The ornamental design for a bowling game target, as shown and described.
